UNITED STATES PATENT OFFICE.

ANDREW LOUIS JOHNSON, OF WINNIPEG, MANITOBA, CANADA, ASSIGNEE TO AMES
HOLDEN McCREADY, LIMITED, OF MONTREAL, QUEBEC, CANADA, A CORPORATION.

SKATING AND HOCKEY BOOT.

1,139,530.

Specification of Letters Patent. Patented May 18, 1915.

Application filed October 8, 1914. Serial No. 865,757.

To all whom it may concern:

Be it known that I, ANDREW LOUIS JOHNSON, a subject of the King of Great Britain, and resident of the city of Winnipeg, Province of Manitoba, Dominion of Canada, have invented certain new and useful Improvements in Skating and Hockey Boots; and I do hereby declare that the following is a full, clear, and exact description of the same.

This invention relates to improvements in the construction of boots and appertains particularly to ankle-supports for hockey boots, having for an object the provision of a more snugly fitting and better bracing boot and ankle-support than heretofore.

The features of the invention will be hereinafter fully described and particularly pointed out in the claims. For full comprehension, however, of my invention, reference should be had to the accompanying drawing forming a part of this specification, in which similar reference characters indicate the same parts and wherein—

Figure 1 is a perspective view of my improved boot; and Fig. 2 is a section through the boot upper.

In the drawings 2 indicates a boot which, being especially adapted for skating, has its upper portion open at the front from the top of the boot to the toe-cap and provided with means for closing the upper by lacing so that the full extent of such upper can be laced snugly about the wearer's foot from the ankle to the toes. The tongue 3 of the boot is secured to and extends upwardly from the rear of the toe-cap and is provided with a pad 4 on its underside.

An ankle-support 5 located within the boot extends from the top to near the bottom thereof and is stitched thereto at the back and also at the sides near the bottom at 6 and extends forwardly to inclose the ankle of the wearer, the top and front margins or forward edges of the support being left free to be snugly bound around the ankle. The full extent of one front margin 5^a of the ankle-support is stitched to one edge of the tongue 3 which is formed with a lateral extension 3^a for this purpose while the other front margin is left free, the ankle-support and tongue being firmly bound about the wearer's ankle by means of a strap 7 which is sewed or otherwise secured at one end to the margin 5^a. This strap is adapted to be passed over the front

of the tongue and the free end thereof passed outwardly through a slot 8 in the boot upper and fastened by a buckle 9 secured upon the exterior of the upper and at the rear of slot 8, strap 7 being formed with 60 holes for adjustment.

It will be seen that by fastening the tongue 3 to the ankle-support both the ankle-support and tongue can be more snugly bound about the wearer's ankle than heretofore and without the liability of the tongue being drawn out of place to either side, while the disadvantage encountered of having the tongue slip down and wrinkle, forming ridges which chafe and blister the 70 foot of the wearer is avoided. Furthermore the tongue is always in proper position and therefore the fastening of the boot and adjustment of the ankle-support can be more quickly effected than when the tongue has 75 to be pulled up and held in place before fastening.

What I claim is as follows:

1. In a hockey boot, the combination with the upper provided with the ordinary lacing means, and a tongue extending from the toe-cap to the top of the upper, of an ankle-support secured within the boot and adapted to embrace the ankle of the wearer, such ankle-support extending at the rear 85 from the bottom of the boot upwardly to the top and forwardly toward the tongue to which one edge or margin of the support is secured, the other edge or margin of the support being free from both upper and 90 tongue but adapted to be overlapped by the latter.

2. In a hockey boot, the combination with the upper provided with the ordinary lacing means and a tongue extending from the toe-cap to the top of the upper, of an ankle-support within the boot and adapted to embrace the ankle of the wearer, such ankle-support being stitched to the boot at the back and also at the sides near the bottom 100 of the boot and extending at the rear from the bottom of the boot upwardly to the top and forwardly toward the tongue to which, near the top, one edge or margin of the support is sewed, the other edge or margin of 105 the support being free from both upper and tongue but adapted to be overlapped by the latter.

3. In a hockey boot, the combination with the upper, provided with the ordinary lac-

ing means, and a tongue extending from the toe-cap to the top of the upper, of an ankle-support secured within the boot and adapted to embrace and be tightened about the ankle of the wearer independent of the ordinary lacing means, such ankle-support extending at the rear from the bottom of the boot upwardly to the top and forwardly toward the tongue to which one edge of the support is secured, and means for tightening and fas-

tening the support independent of the ordinary lacing means.

In testimony whereof, I have signed my name to this specification, in the presence of two subscribing witnesses.

ANDREW LOUIS JOHNSON.
